UNITED STATES PATENT OFFICE.

WALTER HENRY SMITH, OF NEW BRUNSWICK, NEW JERSEY.

VEHICLE-SPRING.

1,124,964.

Specification of Letters Patent. Patented Jan. 12, 1915.

Application filed March 29, 1913. Serial No. 757,534.

To all whom it may concern:

Be it known that I, WALTER H. SMITH, a citizen of the United States, and a resident of New Brunswick, in the county of Middlesex and State of New Jersey, have invented a new and Improved Vehicle-Spring, of which the following is a full, clear, and exact description.

My invention has for its object to provide a vehicle spring having two sets of spring members, one of the sets of spring members being secured to a frame, the other set of spring members being connected with the frame by a link, each of these spring members has a terminal, the terminals being disposed at opposite sides of a connecting member which is normally secured to a frame or axle. Flanges with sleeves are bolted in the recesses, and these flanges are disposed from the sleeves away from the frame, and in and against the adjacent terminals of the spring members, so that bolts may be disposed through the openings in the sleeves in the flanges, for securing the flanges to the connecting member, and additional bolts may be disposed in openings in the flanges, and in the terminals of the spring members, for holding the terminals of the spring members in position. A spiral spring which is provided is connected by tie members having turn buckles, with the link at one of the spring members, and with the frame at the other spring member, so that the spiral spring will give the desired resiliency, when the vehicle on which the spring is used travels over slightly uneven ground. When the vehicle travels over very rough ground, the said spring members take up and do most of the work of the spring. In this way my spring is sensitive when such a quality is desirable, without impairing its usefulness under other conditions.

In vehicle springs as they are now constructed most of the breakage takes place on the rebound. This weakness is done away with with my improved spring, for on the rebound my spring members which are of the usual leaf spring type, will not bend, but, on the contrary, they will straighten. This removes the danger of rupture on the rebound of the spring.

Additional objects of my invention will appear in the following complete specifica-

tion, in which the preferred form of the invention is disclosed.

In the drawings similar characters of reference indicate corresponding parts in all the views, in which—

Figure 1 is an elevation showing my improved spring; Fig. 2 is a sectional view on the line 2—2 of Fig. 3; Fig. 3 is a plan view of Fig. 2; and Fig. 4 is an elevation of one of the leather members, which are disposed between the terminals of the spring members and the connecting member.

By referring to the drawings it will be seen that a frame member 5 is provided, which may be part of an automobile body, and that this frame member 5 has the depending end 6 to which the end 7 of the spring member 8 is articulated. The end 9 of the other spring member 10 is articulated to a link 11, this link 11 being articulated to the frame member 5 at 12.

The spring members 8 and 10 are constructed each of a plurality of leaf springs, which are secured together by the clamps 13. A tie member 14 has a terminal 15, which is articulated to the depending end 6 of the frame member 5, this tie member 14 being connected with a tie member 16 by a turn buckle 17.

A tie member 18 is articulated at its end 19 to the link 11, and the end 9 of the spring member 10, this tie member 18 being connected with a tie member 20 by a turn buckle 21. The tie members 16 and 20 are secured to the spiral spring 22. Disposed below the spiral spring 22 there is a connecting member 23, this connecting member 23 having recesses 24, one at each end in which the terminals 25 of the spring members 8 and 10 are disposed, these terminals 25 being bent away from the frame 5, as shown in Fig. 2 of the drawings.

As a means of securing in the recesses 24 these terminals 25 of the spring members 8 and 10, I provide flanges 26, which have sleeves 27, through which the bolts 28 are disposed, these bolts 28 extending through openings 29 in the connecting member 23 at the sides of the recesses 24. It will be noticed that the flanges 26 extend from the sleeves 27 away from the frame 5, so that at each end of the connecting member 23 a bolt 30 may be disposed through the open-

- ings 31 in the flanges 26, and also through openings 32 in the leaf springs, of which the spring members 8 and 10 are constructed. This bolt 30 has a nut 33, which is disposed 5 through an angular opening 34, in a leather or other non-metallic member 35, this non-metallic member 35 being disposed between the terminals 25 of the spring members 8 and 10, and the ends 36 of the recesses 24.
- 10 The nuts 33 extend beyond the members 35, into openings 37 in the connecting member 23.

As my vehicle spring is constructed, the spiral spring 22 is delicate enough so that 15 it will with the ends 7 and 9 of the spring members 8 and 10, make the vehicle spring sensitive up to a certain point, but beyond that point the bodies of the spring members 8 and 10 will occasion the vehicle spring 20 to stiffen so that while my vehicle spring has the necessary sensitiveness, when this quality is desirable, it does not lessen its effectiveness under other conditions.

While the ordinary vehicle spring is very 25 apt to rupture on the rebound, this danger is wholly eliminated by my vehicle spring, for on the rebound the spring members 8 and 10 straighten, instead of being bent abnormally, as is the case with vehicle springs 30 of other types. The connecting member 23 is secured to an axle 40 by the members 41.

It will be understood that with the connection as it has been described the spring 35 will not be rigidly secured to the axle, but when in use will have a movement which will relieve the spring from much strain.

Having thus described my invention, I 40 claim as new and desire to secure by Letters Patent:

1. In a vehicle spring, a frame, two 45 spring members connected with the frame, a connecting member, the spring members having terminals bent away from the frame, two flanges, one secured at a side of each terminal, and pivoted means for securing the flanges to the connecting members.

2. In a vehicle spring, a frame, two 50 spring members connected with the frame, a connecting member, the spring members having terminals bent away from the frame and one disposed at each side of the connecting member, two flanges disposed against the outer sides of the terminals, and 55 pivotal means for securing the flanges to the connecting members with the flanges extending from the said means and away from the frame.

3. In a vehicle spring, a frame, two 60 spring members connected with the frame, a connecting member, the spring members having terminals bent away from the frame and one disposed at each side of the connecting member, two flanges disposed against the outer sides of the terminals, pivotal 65 means for securing the flanges to the

connecting members with the flanges extending from the said means and away from the frame, and means for securing the flanges to the terminals.

4. In a vehicle spring, a frame, two 70 spring members connected with the frame, a connecting member, the spring members having terminals bent away from the frame, and one disposed at each side of the connecting member, two flanges having sleeves, 75 one of the flanges being disposed at the outer side of each of the terminals, bolts disposed through the sleeves, and securing the flanges to the connecting member, the flanges from the sleeves extending away 80 from the frame, and means for securing the flanges to the terminals.

5. In a vehicle spring, a frame, two 85 spring members connected with the frame, a connecting member, the spring members having terminals bent away from the frame, and one disposed at each side of the connecting member, two flanges having sleeves, 90 one of the flanges being disposed at the outer side of each of the terminals, bolts disposed through the sleeves, and securing the flanges to the connecting member, the flanges from the sleeves extending away 95 from the frame, there being openings in the terminals and in the flanges, and bolts disposed in the last-mentioned openings for securing the terminals of the flanges.

6. In a vehicle spring, a frame, two 100 spring members connected with the frame, a connecting member having two recesses at opposite sides, the spring members having terminals extending away from the frame, and disposed in the recesses, and pivotal means for securing the terminals in the recesses.

7. In a vehicle spring, a frame, two 105 spring members connected with the frame, a connecting member having two recesses at opposite sides, the spring members having terminals extending away from the frame, and disposed in the recesses, two flanges with sleeves, one disposed in each recess, and adjacent the terminal of the connecting member, bolts disposed in the sleeves, and in openings in the connecting member at the 110 sides of the recesses, there being openings in the flanges and the terminals, and bolts disposed in the last-mentioned openings.

8. In a vehicle spring, a frame, two 115 spring members connected with the frame, a connecting member having two recesses at opposite sides, there being openings in the connecting member which communicate with the recesses, spring members having terminals extending away from the frame, and disposed in the recesses, two flanges with sleeves one disposed in each of the recesses, and against one of the terminals, bolts disposed in the sleeves and secured to the connecting member, there being open- 120
